PROPELLER DRIVING MECHANISM

Mathew M. Egan, Fort Worth, Tex.

Application January 23, 1939, Serial No. 252,456

5 Claims. (Cl. 74—389)

This invention relates to propeller driving mechanisms, and its general object is to provide a driving mechanism primarily designed for twin propellers of aircrafts, that includes a housing constructed especially to facilitate readily changing of the gears of the mechanism, so that different sets of gears can be used and varied in accordance with the speed of the engine and the desired speed and direction of rotation of the propellers.

A further object is to provide a driving mechanism for twin propellers that makes provision for thorough lubrication of the parts, as well as ample and firm supporting means for the gears and propeller shafts, so as to reduce and eliminate friction and vibration to a minimum.

Another object is to provide a driving mechanism for twin propellers by which the latter can be driven from a common power shaft in the same or opposite directions, at the same or different speeds, and at a greater or less speed than the normal speed of the engine, and such is brought about by the gear arrangement and the easy gear changing feature previously referred to.

A still further object is to provide a driving mechanism of the character set forth, that is simple in construction, inexpensive to manufacture, easy to install and extremely efficient in operation, use and service.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a vertical sectional view taken through my driving mechanism, with parts in elevation and illustrates fragmentary portions of the twin propellers applied to their respective hubs.

Figure 2 is a front elevation of my mechanism with the propellers applied thereto.

Figure 3 is a sectional view taken approximately on line 3—3 of Figure 1, looking in the direction of the arrows.

Figure 4 is a sectional view taken approximately on line 4—4 of Figure 1, looking in the directions of the arrows.

Figure 5 is a fragmentary sectional view illustrating the mounting of the idle gear of the gear train for the front or slow propeller.

Referring to the drawings in detail, the reference numeral 1 indicates the engine casing to which is fixed the housing of my mechanism by any suitable means, such as screw bolts, while 2 indicates the engine shaft and 3 the shaft for the front propeller, in the form of mechanism shown.

The housing of my mechanism includes a rear section 4 having its main or vertical wall 5 bearing against the engine casing, and formed on the wall 5 is a flanged marginal wall portion 7 having the flange 8 thereof extending outwardly at right angles with respect thereto, for receiving the marginal edge portion of the vertical wall 9 of an intermediate or partition section 10, the latter 15 cooperating with the rear section and a front section 11 to provide the housing of my mechanism and the front section also includes a flanged marginal wall portion 12 having the flange 13 thereof engaged with the marginal edge portion 20 of the intermediate section, the flanges and the marginal edge portion each being provided with registering openings for receiving bolt and nut connections 14 for detachably securing the sections in housing formation, as best shown in 25 Figure 1.

The housing is substantially flat oval shape to provide an enlarged rounded upper portion and a relatively small lower portion, and the vertical wall of the front section has a circular opening 30 in the enlarged portion thereof through which extends a sleeve 15 providing what might be termed a boxing which is formed on and extends outwardly from the partition section to provide a bearing support for the respective shafts 3 35 and 16, the shaft 3 extending through the sleeve 15, as well as through openings in the vertical wall 5 and the partition section 10 and is concentrically arranged with respect to the sleeve 40 and mounted accordingly in bearings 17, while the shaft 16 which is in the form of a sleeve or hollow cylinder surrounds the sleeve 15, but is spaced therefrom by being mounted upon bearings 18, which like the bearings 17 are of the roller type, in the form as shown.

The outer end of the cylindrical shaft is closed by a ring cap 19 that is threaded to the shaft and acts to hold lubricant sealing members 20 and 21 in place between the shaft 16 and the sleeve 15, as well as between the latter and the 50 shaft 3, and a lubricant sealing member 22 is likewise provided about the edge of the opening of the front section 11, for engagement with the shaft 16, as clearly shown in Figure 1. Keyed to the shaft 16 is a hub 23 for the rear propeller 24

and is held thereon by the ring cap 19 while keyed to the reduced end of the shaft 3 is the hub 25 for the front propeller 26 that is held accordingly by a nut as shown.

- 5 The engine shaft 2 extends through bearing openings in the lower portions of the rear and intermediate housing sections and has its outer end mounted in a roller bearing 27 secured within a circular boss 28 disposed about an opening in 10 the vertical wall of the front section, the latter opening being closed by a disk plate 29.
- It will be noted that I have illustrated one set 15 of gears for each of the propeller shafts and the ratio of the gears of the set for the front propeller shaft is approximately two to one while the ratio for the gears of the rear propeller shaft is approximately three to four, and the latter set includes two gears while the former includes three, but both sets may include only two gears 20 and the gears may be of any size, with the result it will be seen that the speed and direction of rotation of the propellers may be varied merely by changing the gears, and the detachable association of the housing sections together with the 25 removability of the other elements makes it possible to change the gears in an easy and expeditious manner.

The set of gears shown, as being in use in the drawings for driving the front propeller shaft, 30 includes what I term a bull or power pinion 30 keyed or otherwise secured to the engine or drive shaft 2, between the rear and intermediate sections, and an idle gear 31 secured to a stub shaft 32 mounted in roller bearings 33, within openings in the parallel or vertical walls of the latter sections. That structure is clearly shown in Figure 5, and it will be noted that the openings are closed by disk plates. The idle gear meshes with the pinion 30 and with a reducing gear 34 keyed 35 to the shaft 3. The bull or power pinion 35 for the set of gears for the rear propeller is likewise shown as being keyed to the engine shaft and directly meshes with the gear 36, which may be keyed to the hollow shaft 16, but is shown as being integral therewith, and the gear 36 bears against an anti-friction bearing 37 of the ball type, disposed between the same and the front section 11, as clearly shown in Figure 1. By using the idle gear 31 and the other gears of the 40 ratio shown and previously set forth, it will be obvious that the propellers will be rotated in opposite directions and the rear propeller will be rotated at a speed of approximately one and one-half times greater than that of the front propeller, but when gears of different ratio are substituted for those shown, the relative speed of the propellers will be changed, and if the idle gear 31 is removed and the gears of the front propeller are of a size to mesh with each other, the front 45 propeller will rotate in the same direction as the rear propeller, as will be apparent.

It will be further obvious that the propeller shafts are amply supported by the use of the intermediate or partition section and the fixed 50 sleeve formed thereon, while the projecting portion of the engine shaft is likewise amply supported, and the supporting features coupled with the bearing arrangement will eliminate or reduce vibration of the parts to a minimum at all speeds 55 of the engine and propellers.

It is thought from the foregoing description that the advantages and novel features of the invention will be readily apparent.

It is to be understood that changes may be 60 made in the construction and in the combination

and arrangement of the several parts, provided that such changes fall within the scope of the appended claims.

What I claim is:

1. A mechanism for driving twin propellers of 5 an aircraft from a common drive shaft, and comprising a sectional gear housing, a shaft for each propeller and concentrically arranged with each other, a section of the housing including a sleeve integral therewith and extending through the 10 housing for disposal exteriorly thereof, said sleeve providing a support for and disposed between the propeller shafts, bearings for the propeller shafts and disposed between the latter and the sleeve, gears for each propeller shaft for individually 15 rotating the same in opposite directions from the drive shaft, and the sections of the housing being removably secured together whereby to allow access to the gears for substituting therefor gears of a different number and ratio to vary the 20 direction of rotation of the propellers and speed thereof in accordance with the speed of the drive shaft.

2. A mechanism for driving twin propellers of 25 an aircraft from a common drive shaft, and comprising a gear housing including rear and front sections and an intermediate partition section, a shaft for one of said propellers, a shaft for the other propeller and surrounding the first propeller shaft, a sleeve integral with the partition 30 section and extending through the front section for disposal exteriorly of the housing, said sleeve providing a support for and disposed between the propeller shafts, gears for each propeller shaft for individually rotating the same from the drive 35 shaft, marginal flanges formed on the rear and front sections, means for securing the flanges to the marginal edge portion of the intermediate section to allow the sections to be separated from each other whereby access may be had to the 40 gears for substituting therefor gears of a different number and ratio to vary the direction of rotation of the propellers and speed thereof in accordance with the speed of the drive shaft.

3. A mechanism for driving twin propellers of 45 an aircraft from a common drive shaft, and comprising a gear housing including rear and front sections and an intermediate partition section, a shaft for one of said propellers, a shaft for the other propeller and surrounding the first propeller shaft, a sleeve integral with the partition section and extending at right angles therefrom for disposal through the front section, said sleeve providing a support for and disposed between the propeller shafts, bearings for the propeller shafts 50 and disposed between the latter and the sleeve, a set of gears for each propeller shaft for rotating the same from the drive shaft, the sets of gears being of different ratio for rotating the propeller shafts at different speeds, an idle gear in 55 one of said sets of gears for rotating one drive shaft in a direction opposite to that of the other, and means for detachably securing the sections together in housing formation.

4. A mechanism for driving twin propellers of 65 an aircraft from a common drive shaft, and comprising a gear housing including rear and front sections and an intermediate partition section, a shaft for one of said propellers and extending through said housing, a hollow cylindrical shaft 70 for the other propeller and surrounding the first propeller shaft, a sleeve integral with the partition section and extending at right angles therefrom for disposal through the front section, said sleeve providing a support for and disposed 75

between the propeller shafts, bearings for the propeller shafts and disposed between the latter and the sleeve, a cap for the outer end of the hollow propeller shaft, lubricant sealing means between the sleeve and propeller shafts and between the casing and the hollow propeller shaft, each of said sections provided with bearings for the drive shaft, a set of gears for each propeller shaft for individually rotating the same from the drive shaft, and means for detachably securing the sections together in housing formation.

5. A mechanism for driving twin propellers of an aircraft from a common drive shaft, and comprising a gear housing including rear and front sections and an intermediate partition section, a shaft for one of said propellers, a hollow shaft for the other propeller and surrounding the first propeller shaft, a sleeve integral with the partition section and extending at right angles thereto from for disposal through the front section, said sleeve providing a support for and disposed be-

tween the propeller shafts, bearings for the propeller shafts and disposed between the latter and the sleeve, each of said sections provided with bearings for the drive shaft, a set of gears for each of the propeller shafts for rotating the same from the drive shaft, the set of gears for the first propeller shaft including a relatively small gear keyed to the drive shaft, a relatively large gear keyed to the first propeller shaft, an idle gear meshing with the relatively small and large gears for rotating the first propeller shaft in the same direction as that of the drive shaft, the set of gears for the hollow shaft including a relatively small gear keyed to the drive shaft and a relative large gear fixed to the hollow propeller shaft and meshing with the second mentioned small gear for rotating the hollow propeller shaft in a direction opposite to that of the other propeller shaft, and means for detachably securing the sections together in housing formation.

MATHEW M. EGAN.
